(57) **CLAIM**

The ornamental design for a combined ceiling fan housing and fan blade arms, as shown and described.

DESCRIPTION

FIG. 1 is lower front side perspective view of a combined ceiling fan housing and fan blade arms.

FIG. 2 is an upper front side perspective view of the combined ceiling fan housing and fan blade arms of FIG. 1.

FIG. 3 is a reduced bottom view of the combined ceiling fan housing and fan blade arms of FIG. 1.

FIG. 4 is a reduced top view of the combined ceiling fan housing and fan blade arms of FIG. 1.

FIG. 5 is a front side view of the combined ceiling fan housing and fan blade arms of FIG. 1.

FIG. 6 is a rear side view of the combined ceiling fan housing and fan blade arms of FIG. 1.

FIG. 7 is a right side view of the combined ceiling fan housing and fan blade arms of FIG. 1; and,

FIG. 8 is a left side view of the combined ceiling fan housing and fan blade arms of FIG. 1.

The broken line showing of the canopy, support rod, housing upper vents, and upper fastener holes, light shade and blades is included for the purpose of illustrating environmental structure and forms no part of the claimed design.
